UNITED STATES PATENT OFFICE.

CHARLES RUFUS REID, OF HEIDELBERG, MISSISSIPPI.

ROTARY ENGINE.

No. 877,733.

Specification of Letters Patent.

Patented Jan. 28, 1908.

Application filed October 22, 1907. Serial No. 398,627.

To all whom it may concern:

Be it known that I, CHARLES RUFUS REID, a citizen of the United States, residing at Heidelberg, in the county of Jasper and State 5 of Mississippi, have invented a new and useful Rotary Steam-Engine, of which the following is a specification.

This invention relates to rotary engines, and has for its principal object to provide a 10 novel form of engine in which the steam or other agent used for motive power may be employed with the utmost economy and efficiency.

A further object of the invention is to construct a machine of this type which may be 15 readily reversed and in which the quantity of steam or other fluid employed may be accurately adjusted either manually or automatically in accordance with the speed and 20 load.

A still further object of the invention is to provide a novel form of cylinder and cylinder 25 packing arranged in such manner as to prevent leakage without however exercising un- due frictional resistance to the movement of 30 the piston.

A still further object of the invention is to provide a novel form of packing for the piston wing or wings for preventing any leakage 35 of steam beyond the wings while in operation.

A still further object of the invention is to provide an improved means for actuating the valves and the cylinder abutments.

With these and other objects in view, as 35 will more fully hereinafter appear, the invention consists in certain novel features of construction and arrangement of parts, herein- after fully described, illustrated in the accompanying drawings, and particularly 40 pointed out in the appended claims, it being understood that various changes in the form, proportions, size and minor details of the structure may be made without departing from the spirit or sacrificing any of the ad- 45 vantages of the invention.

In the accompanying drawings:—Figure 1 is a longitudinal sectional view of a rotary engine constructed in accordance with the invention. Fig. 2 is a transverse sectional view of the same on the line 2—2 of Fig. 1. 50 Fig. 3 is a sectional plan view through one of the valve chests. Fig. 4 is a vertical section through a portion of one of the valve chests. Fig. 5 is a similar view through a portion of 55 the main steam chest. Fig. 6 is an elevation of the reversing lever and its connections.

Fig. 7 is a detail perspective view of the valve operating rod connections. Fig. 8 is a detail perspective view of one of the movable piston wings, detached. 60

Similar numerals of reference are employed to indicate corresponding parts throughout the several figures of the drawings.

The base or sole plate 10 of the engine may 65 be of any desired shape and size in accordance with the character of work which the engine is to perform, and, in the present instance, is shown in the form of an approximately rectangular frame that is provided with bearings 11 for the reception of the shaft 12, and said shaft is further provided with a central bearing 13 formed on a cross bar extending 70 across and carried by the central portion of the base.

The shaft may be connected to the mechanism to be driven in any suitable manner, but preferably is extended at both ends to points beyond the bed plate, and is provided with pulleys of different size from which 80 power may be transmitted.

Secured to the shaft are two pistons 14 and 15, each having a pair of diametrically opposed wings 16, the piston and wings being of precisely the same construction, but the 85 wing of one piston being disposed in a plane at a right angle to those of the other piston, so that there is always live steam pressure on at least one of the wings, and power is, therefore, constantly exerted on the main 90 shaft.

The pistons 14 and 15 are disposed, respectively, in cylinders 18, 19, these cylinders being of like construction and each being provided with a pair of laterally extended 95 horizontal ears 20 which rest on the base and are confined in place by straps 21. Each cylinder is formed of two sections 23, 24, the section 23 comprising one of the heads, and the outer circular ring of the cylinder, while 100 the section 24 is in the form of a removable head, and between this head and the other section of the cylinder is arranged a packing ring 25 in order to prevent the escape of steam. The two parts of each cylinder are 105 held in place by bolts 26 or similar securing members, and the central portion of each head is perforated to form a circular opening 28 of much greater diameter than that of the shaft.

The pistons and cylinders are concentric and each side of each piston is provided with

a cylindrical hub extension 29 passing through the opening 28, a narrow annular space being left between the periphery of the hub extension and the wall of the opening. In this annular space is placed a packing ring 30 that is held in place by an annular gland ring 31 that is secured in place by bolts 32, the bolts passing through the outer flange of the gland ring, so that the latter 5 may be adjusted for the purpose of compressing the packing to any desired extent. This packing will prevent any leakage of steam around the central portion of the cylinder, and at the same time presents a relatively 10 small friction surface to the piston. 15

Each of the piston wings 16 is provided with a slot 34 that extends on a line radiating from the axis of the shaft 12, the slot being preferably cut down from the outermost 20 edge of the wing to a point in alignment with the periphery of the hub extensions. Extending across this slot is a rectangular bar 35 having an opening for the passage of a helical compression spring, the axis of which 25 is parallel with that of the shaft. Mounted in the slot are two overlapping blades 37 which are notched at their inner edges for the reception of the bar 35, and which are pressed outward into engagement with the 30 cylinder heads by means of a spring 36. The inner ends of these blades are further engaged by a pair of helical compression springs 38 that are seated against the bottom wall of the slot 34. These springs serve to force the 35 blades outward into engagement with the inner circular wall of the cylinder, so that a steam tight joint is formed all around the piston wing and the passage of the steam or other actuating fluid is prevented. 40

Above each of the cylinders is a double steam chest divided into two separate compartments 40 and 41 by a centrally disposed vertical partition 42. This partition is provided with a vertical opening of rectangular 45 form in cross section for the reception of a vertically movable abutment 43, the lower end of which extends into the cylinder and the cylinder heads are provided with radial grooves to receive the edges of such abutment and hold the same from movement 50 under the action of the steam. The upper end of the abutment is turned outward to form an arm 45 that passes through the bifurcated upper end of a rod 46, said rod being 55 preferably of non-circular form in cross section and being guided by an opening in the cover 47 of the steam chest and by an auxiliary guard plate 48 that is secured to the outer wall of the chest. The lower end of 60 the rod 46 is provided with a projecting pin or roller 49 that enters a cam slot 50 formed in a disk 51 that is rigidly secured to the shaft 12, and which is preferably, also, secured to the adjacent piston as by bolts 52. 65

The cam slot 50 is for the most part circular

in form, and is provided with two rises corresponding to the two piston wings, so that during rotation of the cam, the abutment will be moved out twice during each revolution of the cam and piston, and each time 70 will be lifted over the projecting piston wing, and then moved down back to the wing until its inner edge engages against the periphery of the piston body. To provide some slight freedom of movement, and in order to hold 75 the inner end of the abutment down into engagement with the piston periphery, a leaf spring 52' is introduced between the upper edge of the arm 45 and the transverse bolt or bar 53 that is carried by the upper portion of 80 the rod 46.

Leakage of steam around the abutment is guarded against by a packing ring 55, and gland 56, the latter being secured to the top or cover 47 of the steam chest in such manner as to compress the packing and hold the same tightly against the abutment, so that the steam or other actuating fluid can not escape. 85

Leading from the steam chest 40 to the cylinder is a port 60 which opens into the cylinder at one side of the abutment, and leading from the chest 41 is a similar port 61 that opens into the cylinder at the opposite side of the abutment. It is obvious that 90 both of these ports cannot be utilized at the same time, and provision is made, as will be hereinafter described, for cutting off the supply of steam to one or other of the chests in accordance with the direction in which the 100 engine is to rotate.

The entrance ends of the ports 60 and 61 are in the outer vertical walls of the chests and are under the control of a pair of valves 63. These valves are carried by pins 64 that 105 project through vertical slots formed in the wall of the chest, the slots being permanently covered by the valves in order to prevent leakage of steam. The outer ends of these pins are secured to vertical rods or bars 65 110 that are disposed in parallel relation, and the upper ends of these bars or rods are turned outward, forming arms 66 that are adjustably secured by nuts 67 to the upper threaded ends of a pair of rods 68. The 115 lower ends of these rods 68 are secured together by a cross bar 70 that is guided by the plates 48 and from this cross bar 70 projects a pin or anti-friction roller 71 that fits in a cam groove 72 in the disk 51. This groove 120 is of such shape as to open and close the valves at proper intervals, and while both valves are opened, steam passes only from that chest which is in communication with the main supply, the exhaust steam escaping through a port 74 at the bottom of the cylinder, and said port being connected, if necessary, to an exhaust pipe which may lead off to some suitable point of discharge. 125

The main steam pipe 80, which may be 130

supplied with a suitable throttle valve under the control of any ordinary form of governor, leads to a main steam chest 81, in which are two valves 82, designed to control 5 two ports 83 and 84 that lead to the chests 40, 41 by one of the cylinders, and it will be noted that the two chests 40 are in communication through pipes 85, while the chests 41 are in communication through pipes 86. 10 These valves are carried by pins 88 projecting through vertical slots in the end walls of the main chest, and said pins are carried by vertically guided arms 89 which are engaged by the opposite ends of a lever 90 that is pivoted on a pin 91. These arms are connected to a lever 92 which may be moved for the purpose of shifting the valve so as to allow the steam to flow from the main chest to the two auxiliary chests 40, or to the two auxiliary chests 41, so that the engine may be 15 made to rotate in either direction.

In operation, the steam is admitted to either the port 60 or the port 61 between the piston wing and the abutment and operates 20 to drive the piston wing away from the abutment, thus transmitting rotative movement to the piston and the shaft. The piston is rotated through approximately a half revolution and the steam finally escapes at the 25 bottom of the cylinder. The positive driving action is assured by locating the piston wings of one piston at a right angle to those of the other, so that driving movement is always being imparted to the shaft, no matter what the position of the wings may be. 30 At the end of each half revolution, the abutment is raised until the piston wing has passed the vertical plane of the abutment, and then is lowered into engagement with the periphery of said piston.

It is obvious that the engine may be placed under control of any suitable form of governor to provide for variation in the speed and load.

I claim:—

45 1. In a rotary engine, a cylinder, a piston arranged therein and provided with a projecting wing, a shaft carrying said piston, a double groove cam disk carried by the shaft, an abutment, a double steam chest, means 50 for controlling the supply of steam to said chest, ports leading from the chests to the cylinder and opening respectively on opposite sides of the abutment, a pair of valves controlling the ports, valve rods, a block 55 connecting said valve rods and provided with a projection entering one of the cam grooves, and an abutment actuating rod having a member entering the other cam groove.

2. In a rotary engine, a cylinder having 60 enlarged openings in its opposite heads, a piston arranged within the cylinder and provided with circular hub extensions, projecting through and beyond said openings, a

yieldable packing ring disposed in the annular space formed between each hub extension 65 and the adjacent wall of the opening, a gland ring bearing on the packing ring and having an annular flange at a point outside the cylinder, and securing bolts extending through such flange for adjusting the degree 70 of pressure on the packing ring.

3. In a rotary engine, a frame, a pair of cylinders, lugs extending from the cylinders and resting on the frame, straps extending across said lugs and confining the cylinders in 75 place, a shaft extending through the cylinders, a pair of pistons mounted on the shafts and provided with wings, the wings of one piston being disposed at a right angle to those of the other piston, a pair of steam 80 chests for each cylinder, ports leading from the chests to the cylinders, a main supply chest having ported communication with the cylinder chest, a pair of valves arranged in the supply chest and controlling the flow of 85 steam therefrom, valves controlling the flow of steam from the cylinder chests to the cylinders, means for actuating said valves, and cam actuated abutments working in each of the cylinders. 90

4. In a rotary engine, a cylinder, a piston, a shaft carrying the piston, a cam disk on the shaft, a movable abutment extending outside the cylinder and provided with a laterally projected arm, an abutment operating 95 rod having at one end a projection engaging the cam disk, and bifurcated at its opposite end to receive the abutment arm, a bolt extending across the bifurcated portion of the rod above the arm, and a spring interposed 100 between the bolt and the outer side of the arm to hold the abutment yieldably against the piston.

5. In a rotary engine, a cylinder, a piston arranged therein and provided with a projecting wing, the wing being radially slotted and provided with a cross bar extending across the slot, the cross bar having a transversely extending opening, a pair of overlapping blades arranged in the slot and having their inner edges recessed to receive the bar, a spring extending through the opening and tending to force the blades laterally against the heads of the cylinder, and springs seated in the bottom of the slot and tending 110 to thrust the plates outward into engagement with the circular inner wall of the cylinder. 115

In testimony that I claim the foregoing as my own, I have hereto affixed my signature 120 in the presence of two witnesses.

CHARLES RUFUS REID.
